UNITED STATES PATENT OFFICE.

GEORGE M. HENDERSON, OF FARRELL, PENNSYLVANIA.

REEL.

1,406,010.

Specification of Letters Patent. Patented Feb. 7, 1922.

Application filed February 10, 1921. Serial No. 443,889.

To all whom it may concern:

Be it known that I, GEORGE M. HENDERSON, a subject of the King of England, residing at Farrell, in the county of Mercer and State of Pennsylvania, have invented certain new and useful Improvements in Reels; and I do declare the following to be a full, clear, and exact description of the invention, such as will enable others skilled in the art to which it appertains to make and use the same.

This invention relates to an improved reel upon which rope, wire, or the like is wound for convenience in shipping and storing.

The principal object of the invention is to provide a device of this kind which is of extreme simplicity in construction, being composed of a plurality of wire loops and connectors for these loops in the form of plates, the amount of wire and material necessary to form the reel being reduced to a minimum. Thus, the cost of manufacture of the reel is reduced considerably and a reel is provided which is as equally advantageous and effective as any similar reels now on the market.

Another object of the invention is to provide a reel wherein the number of parts used to construct it is reduced to a minimum; one which is very rigid and strong in construction and capable of withstanding rough usage; one in which the parts can, if desired, be easily and readily separated so that a compact package may be had for convenience in storage and transportation.

Other objects and advantages of the invention will be apparent during the course of the following description.

In the accompanying drawings, forming a part of this specification and in which like numerals are employed to designate like parts throughout the same:

Figure 1 is an end elevation.

Figure 2 is a front elevation.

Figure 3 is a section taken on the line 3—3 of Fig. 1.

Figures 4, 5, and 6 are detail perspective views of parts of the reel disconnected.

Referring to the drawings, wherein the preferred embodiment of the invention is clearly illustrated, it will be seen that the reel is formed from four wire loops, two of which are relatively short, of substantially the same length, and are here indicated by the numeral 1. These loops are arranged in

spaced relationship at points opposite one another. The two remaining loops 2 are slightly longer than the two loops just referred to, and they are disposed at right angles to and extend through the loops 1 at points intermediate the ends of the latter, these loops 2 being also spaced from one another. Loops 2 have their opposite ends bent at right angles to the body portion as indicated at 3, these ends extending in a substantial plane with the loops 1 and forming with the latter heads for the reel. The intermediate horizontal portions of the loops 2 form the hub of the reel. The loops in all instances are formed from a single piece of wire bent into the shape shown, the free ends being soldered, welded, or otherwise secured together, as indicated at the points 4.

I make use of novel means for securing the respective loops together at their point of engagement with each other. While this means may be of some other construction, it is preferably in the form of metal plates 5 of substantially rectangular shape which may well be termed here as "end plates." As shown, each plate is provided at its corners with a notch 6 which forms a seat. Adjacent to each seat are integral straps or tongues 7 which are adapted to be wrapped around the strands of wire of the laterally bent ends of the loops 2. It is to be noted, that in order to prevent accidental displacement of the wires from the aforesaid seats, hooks 8 are provided at these points.

In constructing the reel, I first seat the loops 2 in the notches 6, after which I bend the opposite ends of these loops laterally so that they extend in a substantial plane with the plates 5. Sometimes, the ends of the wire loops 2 are bent previous to connection to the plates 5. After the loops 2 are placed in the seats in the manner just described, I place the loops 1 against the outer faces of the end plates 5, causing them to rest in the corners formed by the bending of the wire loops 2. Then, I wrap the tongues 7 about the vertical portions of the laterally bent ends of the loops 2 in the manner disclosed. Thus, the device is completed and easy and possible displacement and disconnection of the parts is overcome. However, when it is desired, the tongue 7 can be unwrapped and the several parts of the device can be easily and readily disconnected so that they may be arranged in a compact package for shipping.

in a knock-down form. I wish to mention at this point, that the loops 1 are provided intermediate their ends with opposed bends 9 forming seats in which the adjacent portions of the wire loops 2 are received. This construction and arrangement serves to prevent slippage and accidental displacement of these loops 1. I may also direct attention to the fact that the end plates 5 are centrally 10 apertured as designated at 10 for passage of a shaft or the like on which the reel is placed for the purpose of winding or unwinding material on it or from it, as the case may be.

From the foregoing description, it will be 15 seen that I have constructed a simple and effective reel which embodies extremely few and inexpensive parts connected and arranged in such a manner that they may be separated for arranging them in a compact 20 package for convenience of shipping and storing. The amount of wire which I employ in the formation of my reel is reduced to a minimum, there being four 25 lengths of wire employed for the formation of four loops, two of which constitute the hub portion of the reel and also form a part of the head of the latter. In some instances, a fairly effective and advantageous reel can be constructed by omitting the loops 30 1 and using only the two loops 2 with the end plates for connecting them and spacing them. However, the form and arrangement shown and described is preferred. These 35 and other advantages and features of the invention have, no doubt, become apparent from the foregoing description and drawings.

A careful consideration of the description taken in connection with the drawings, 40 is thought to be sufficient to enable persons familiar with devices of this class, to obtain a clear understanding of the same. Therefore, a more lengthy description is deemed unnecessary.

45 Since probably the best results can be obtained with the construction and arrangement herein shown and described, this construction and arrangement is to be taken as a preferred embodiment of the invention.

50 However, I wish that it be understood that various minor changes in the shape, size, and arrangement of parts may be resorted to without departing from the spirit of the invention or the scope of the subjoined 55 claims.

I claim:

1. A reel comprising a pair of spaced wire loops arranged opposite one another, a second pair of spaced wire loops extending 60 across the adjacent loops intermediate the ends of the latter, being disposed at right angles thereto, said second loops having their ends bent at right angles to their body portions so as to extend in a substantial plane with the first named loops, and means 65

connecting both pairs of loops together at their points of engagement with one another.

2. The structure set forth in claim 1, the connecting means being a pair of plates provided with seats for receiving the wire loops, and retaining tongues for holding the wire loops in the seats. 70

3. A reel comprising a pair of elongated loops formed from a single length of wire 75 having their ends connected together, and a pair of connecting plates for the loops, for retaining the latter in spaced relation, said plates being disposed intermediate the ends of said loops, each of the loops having its 80 opposite ends bent laterally to extend in a plane with said plates, the intermediate portions of the loops constituting the hub of the reel, and the laterally bent ends constituting the heads. 85

4. A reel of the class described comprising a pair of spaced oppositely disposed relatively short oval-shaped wire loops, a second pair of spaced oppositely disposed relatively long oval-shaped wire loops passing through the first loops and engaging the latter at points intermediate their ends, said first loops being formed with oppositely disposed bends intermediate their ends constituting pockets receiving the adjacent 95 wires of the second pair of loops, the second loops having their opposite ends bent laterally in opposite directions forming with the first named loops, heads for the reel, the intermediate portions of the second loops 100 constituting a hub, and substantially square centrally apertured connecting plates for the two pairs of loops, each plate being provided at each of its corners with a seat receiving the adjacent wires of the aforesaid 105 loops, being also provided near these seats with tongues bent around one of the adjacent wires for retaining both of said wires in their seats. 110

5. A reel of the class described comprising a pair of spaced end plates of rectangular formation, each plate being provided with a central opening for passage of a supporting rod or the like, being also provided at its corners with notches, on one side of which are hooks, and on the opposite sides of which are relatively long extensions forming tongues, and a pair of spaced wire loops having their intermediate portions arranged in said seats, said loops having their opposite ends bent laterally in a plane with said plates and the aforesaid tongues being wrapped around the vertical portions of the laterally bent ends to retain said loops in the seats. 115 120 125

6. A reel of the class described comprising a pair of elongated oppositely disposed wire loops, each of which has its opposite ends bent at right angles, the angularly bent ends of one loop extending in an oppo- 130

site direction to those of the opposite loop, and end plates for connecting and holding the loops in spaced relation, said plates having seats formed at their corners for receiving the bends of the wire loops, and said plates also having means for maintaining the bends in said seats, whereby the bent

ends of the loops together with the plates constitute heads for the reel and the intermediate portion of the loops forms a hub 10 therefor.

In testimony whereof I have hereunto set my hand.

GEORGE M. HENDERSON.
